(57) **CLAIM**

The ornamental design for a household apparatus for preventing dental calculus and periodontosis, as shown and described.

DESCRIPTION

FIG. 1 is a front view of my new design of household apparatus for preventing dental calculus and periodontosis;
FIG. 2 is a rear view thereof;
FIG. 3 is a right side view thereof;
FIG. 4 is a left side view thereof;
FIG. 5 is a plane view thereof;
FIG. 6 is a bottom view thereof;
FIG. 7 is an explanatory drawing absent the main housing;
FIG. 8 is a front view of handy probe thereof;
FIG. 9 is a right side view of handy probe thereof;
FIG. 10 is a left side view of handy probe thereof;
FIG. 11 is a plane view of handy probe thereof; and,
FIG. 12 is a bottom view of handy probe thereof.

The broken line showing is for illustrative purposes only and forms no part of the claimed design.
